CONTAINER FOR BOOKS OR SIMILAR ARTICLES

Bennet B. Harvey and Joseph D. Landes, Jr., Chicago, Ill., assignors to Rand McNally & Company, a corporation of Illinois

Application July 30, 1949, Serial No. 4,218

Term of patent 14 years

(Cl. D58—12.6)

To all whom it may concern:

Be it known that we, Bennet B. Harvey and Joseph D. Landes, Jr., both citizens of the United States and residing respectively in the city of Chicago, county of Cook, and State of Illinois, and Evanston, county of Cook, and State of Illinois, have invented a new, original, and ornamental Design for a Container for Books or Similar Articles, of which the following is a specification, reference being had to the accompanying drawings, forming part thereof.

Figure 1 is an exploded perspective view of a container for books or similar articles showing my new design;

The back of the container is plain.

We claim:

The ornamental design for a container for books or similar articles, as shown and described.

BENNET B. HARVEY.

JOSEPH D. LANDES, JR.
